RECOVERY OF THE PRODUCTS OF DESTRUCTIVE HYDROGENATION

Mathias Pier, Heidelberg, and Karl Winkler, Ludwigshafen-on-the-Rhine, Germany, assignors, by mesne assignments, to Standard-I. G. Company, Linden, N. J., a corporation of Delaware

Application September 9, 1929, Serial No. 391,508,
and in Germany September 22, 1928

4 Claims. (Cl. 196—53)

This invention relates to improvements in the recovery of the products of destructive hydrogenation and cracking processes which are hereinafter referred to for the sake of brevity as the conversion of distillable carbonaceous materials by heat treatment.

The gaseous and vaporous products which leave the reaction vessels during the destructive hydrogenation of distillable carbonaceous materials such as coal, tars, mineral oils, extraction, conversion, distillation products thereof and the like, or during the cracking of mineral oils, tars and the like, and which contain volatile sulphur compounds and difficultly condensable hydrocarbons in addition to readily condensable hydrocarbons, are as a rule washed with a washing oil, after the readily condensable products have been removed by cooling, in order to remove as completely as possible the non-condensed hydrocarbons and the sulphur compounds, which during the condensation are only partly dissolved by the condensate. The pressure is preferably not released from the gases before the said washing process is complete in case pressure be employed.

We have now found that the washing can be simplified, and other advantages may be obtained at the same time, by simultaneously carrying out the condensation of the vapors, and the washing of the gases by means of a washing oil, which is a solvent for sulphur compounds and hydrocarbons. As examples of washing oils may be mentioned for example hydrocarbon oils of high boiling point, such as tar oils, middle oils, mineral oil fractions of high boiling point range, destructive hydrogenation products and the like. The process in accordance with the present invention is preferably carried out by spraying the washing oil into the gases and vapors leaving the reaction chamber before they enter the condenser. In this manner an excellent washing out of hydrocarbons and sulphur compounds is effected in the condenser simultaneously with the condensation of the vapors.

The process thus becomes much simpler in operation, since by working in this manner a special plant for the washing is dispensed with. Moreover the effluent gases and vapors are cooled to a certain extent by the washing oil itself.

By a suitable choice of the quantity and temperature of the washing oil the cooling may even be effected wholly or at least to the greater part in this manner. It is also advantageous to work in such a manner that the products leaving the reaction and the washing oil are introduced to-

gether into the condenser from below, because in this manner an active and thorough agitation of the gases and vapors with the washing oil is secured. The condensed and dissolved reaction products are collected in a special vessel where they are separated from the uncondensed gases which are free to a great extent, or practically completely from the hydrocarbons and the sulphur compounds. If the washing is carried out under pressure, the gaseous hydrocarbons, sulphuretted hydrogen and the like may be obtained from the mixture of washing oil and condensed products by fractionally releasing the pressure. The washing oil may be separated and returned for employment in the process again.

The destructive hydrogenation process referred to above is usually carried out at temperatures of between about 300 and 700° centigrade and preferably at between about 380 and 550° centigrade. Catalysts immune from poisoning by sulphur are preferably employed in the said process, and in particular such comprising a metal in a free or combined state from the sixth group of the periodic system such as molybdenum, tungsten or chromium, or cobalt in a free or combined state. Where pressure be employed, those of about 20 atmospheres or more are very suitable as for example of between 20 and 50 atmospheres, 100, 200, 300, 500, 1000, 2000, 3000 or 5000 atmospheres or even more. Pressures as low as 5 or 10 atmospheres may, however, be employed if highly active catalysts, such as molybdenum, are utilized to effect the conversion. The aforesaid cracking process may also be carried out under pressure.

The present invention will be further described with reference to the accompanying drawing which represents in a diagrammatic manner a plant which is particularly suitable for carrying out the process according to this invention.

Referring to this drawing in detail, hydrogen is introduced at valve 1 and pumped by pump 2 into the pipe 3 at the end of which it is mixed with carbonaceous materials introduced by means of pump 5. The mixture of hydrogen and carbonaceous materials is then passed through the preheating coil 7 and from thence to the preheating device 9, heated by electrical means and in which it is brought to the reaction temperature. The hot materials enter at 10 into the reaction vessel 11 filled with a suitable catalyst. In this vessel the materials undergo destructive hydrogenation. The converted vapors leave vessel 11 at 8, pass through pipe 12 and
